(57) **CLAIM**

The ornamental design for a garage LED light, as shown and described.

DESCRIPTION

FIG. 1 is a first perspective view of a garage LED light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the garage LED light in which the design is embodied that form no part of the claimed design.
